UNITED STATES PATENT OFFICE.

WALTER GLAESER, OF FULLERTON, PENNSYLVANIA, ASSIGNOR, BY MESNE ASSIGNMENTS, TO POTASH EXTRACTION CORPORATION, OF NEW YORK, N. Y., A CORPORATION OF NEW YORK.

APPARATUS FOR TREATING SILICATES.

1,347,024.

Specification of Letters Patent.

Patented July 20, 1920.

Application filed September 19, 1917. Serial No. 192,182.

To all whom it may concern:

Be it known that I, WALTER GLAESER, a subject of the German Emperor, and a resident of Fullerton, county of Lehigh, and 5 State of Pennsylvania, have invented a new and useful Improvement in Apparatus for Treating Silicates, of which the following is a specification, the principle of the invention being herein explained and the best mode in 10 which I have contemplated applying that principle, so as to distinguish it from other inventions.

The present invention, relating, as indicated, to a furnace apparatus is more particularly concerned with the provision of 15 mechanism for treating materials in the absence of oxidizing conditions and in the absence of moisture. A further object of the invention is the provision of a continuously 20 operating and automatic apparatus for carrying out the several steps involved in such a treatment of materials for the above purpose. To the accomplishment of the foregoing and related ends, said invention, then, 25 consists of the means hereinafter fully described and particularly pointed out in the claims.

The annexed drawing and the following description set forth in detail certain mechanism embodying the invention, such disclosed means constituting, however, but one 30 of various mechanical forms in which the principle of the invention may be used.

In said annexed drawings:—

35 Figure 1 is a side elevation partially in section of a conveyer, crusher and hopper; Fig. 2 is a similar view showing the upper end of the rotary kiln and the material feeding means associated therewith and leading 40 from the hopper; Fig. 3 is a similar view of the kiln and the furnace and stack chamber; Fig. 4 is a side elevation of the discharge hopper; and Fig. 5 is a section on the line 5—5 in Fig. 3.

45 In Fig. 1 there is shown the end of an indirect drier in the form of a conduit 1, the material sliding through this drier, by reason of the inclined position of the same, and moving into a second inclined conduit 2, at 50 the lower end of which are disposed crushing rolls 3. These rolls 3 are adapted to grind the material to a powder. The material upon passing through the rolls 3 falls

into the lower end of a conveyer conduit 4, in which is mounted a suitable type of conveyer 5, which is adapted to move the material to the upper end of the conduit 4, from which it is delivered into a hopper 6. The use of a conveyer between the feeding hopper 6 and the drier 1 is not of course 55 necessary, for these two elements can be so placed that the drier will feed directly into the hopper, but this is difficult in the ordinary installations of the apparatus by reason of the great height at which the drier 60 must be located to be above the hopper.

The hopper 6 is in the form of a cylindrical vertically disposed conduit having a conically formed bottom 7, terminating in a conduit 8 which is connected with a horizontally disposed feeding conduit 9. In the conduit 8 there is provided a valve preferably in the form of a horizontal slide 10, by means of which the supply of material to the conduit 9 is controlled. In the conduit 70 9 there is mounted a conveyer or feeder, preferably in the form of a screw 11, attached to the right end of which is a shaft 12 extending exteriorly of the conduit 9 and operated by means of the sprocket 13, which 75 may be driven from any suitable source of power. The conduit 9 is supported in the casing 15 by means of a bracket or spider 17. At its other end the feed conduit 9 is received within the upper end of a slightly inclined rotatable kiln 14. The connection between the conduit 9 and the kiln 14 is made tight by housing the end of the former in a chamber 15, which is provided with bearing flanges 16 forming a tight joint about the 80 end of the kiln 14 and permitting the latter to rotate therein. The size and form of the chamber 15 is of course immaterial so long as it is of sufficient size to house the conduit 9, and to also house a small tube 18 extending from within the end of the kiln 85 through the chamber 15 where it is preferably connected to a fan 19 leading to a condenser not shown for withdrawing and condensing any moisture or other condensable material which may be generated in the kiln. The kiln 14 is of considerable length and is inclined at a very slight angle to the horizontal, the angle being sufficient to permit the conduit to feed the material therealong 90 by its own rotation, this feeding action be-

ing assisted and controlled by means of internal longitudinally disposed flanges 20, which serve to lift the material as the kiln rotates and then drop the same into the bottom. The precise construction of the kiln will be determined to a large extent by the output required, and it may be built up of a number of sections bolted together, or it may be formed as an integral tube depending upon this requirement.

At its lower or discharge end the kiln 14 enters a receiver 21, the joint between the kiln and receiver being made air tight by flanges 22 and 23 on the receiver and kiln respectively; these flanges being provided with suitable packing material therebetween. The receiver is preferably in the form of a cylindrical chamber having a conical bottom opening into a measuring discharge chute 50 in which are spaced gates or slides 51 and 52. The material may be allowed to deposit on the gate 52 until above the level of the gate 51, which is open meanwhile, and the latter may then be closed, and the material between the gates drawn off. The principal function of the double gates is to prevent the admission of air to the apparatus while material is being cooled and withdrawn. The kiln is supported upon rollers 24 and 25 mounted on suitable supporting piers 26, placed adjacent to the ends of the kiln and are supported intermediate these ends in an outside shell 27, which is disposed concentrically about the kiln 14 and maintained in such position by means of spiders 28 attached to the kiln and extending to the outer shell. This shell is provided with a plurality of laterally extending transverse flanges or tires 29, which ride upon suitable rollers 30 mounted upon supports 31. The shell and kiln are rotated as a unit by means of a pinion 32 which mesh with a large gear 33 attached to the outside shell between the tires 29 and the pinion 32 and is driven at a speed which will give the kiln a rotation of a few turns a minute.

The shell 27 extends at its two ends into a furnace chamber 35 and stack chamber 36 respectively, these chambers being formed of suitable refractory material and being built up from the floor level to a point above the shell 27. The furnace chamber 35 is of substantially rectangular cross section, being provided with grate bars 37 and a furnace arch 38 disposed beneath the kiln 14 to protect the same from the hottest gases. The products of combustion from the furnace pass upwardly through the furnace chamber around the protecting arch 37 and then pass around the kiln 14 through the shell 27 to the stack chamber 36 which is

also of substantially rectangular cross section and leads to a stack 39.

It has already been stated that this apparatus is intended for the treatment of materials under non-oxidizing and perfectly dry conditions. Accordingly the two ends of the kiln are sealed tightly against the introduction of air and a condensing tube 18 is provided to withdraw and condense whatever moisture may be present in the material as it enters the kiln. In order to economize on the heating as much as possible it is desirable to prevent the escape of products of combustion while passing through the shell 27 and the two ends of this shell are therefore constructed to rotate snugly within suitable openings formed in the chambers 35 and 36, although no precautions need to be taken to make these two joints absolutely air tight.

The temperature which I have found to exist in the apparatus varies considerable in the various parts of the kiln, the temperature being highest of course in that portion of the kiln in the furnace chamber.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In apparatus of the character described, the combination of a stationary furnace chamber, a stationary stack chamber spaced therefrom, a rotary tubular shell connecting and affording communication between said chambers, a kiln mounted in said shell and extending through said chambers and projecting beyond the front wall of said furnace chamber, and receiving means associated with the projecting end of said kiln beyond the wall of the furnace chamber.

2. In apparatus of the character described, the combination of a stationary furnace chamber, a stationary stack chamber spaced therefrom, a rotary tubular shell connecting and affording communication between said chambers, a kiln mounted in said shell and extending through said chambers and projecting beyond the front wall of said furnace chamber, and measuring receiving means associated with the projecting end of said kiln beyond the wall of the furnace chamber, said receiving means and the projecting end of said kiln serving as cooling means for the material being treated.

Signed by me, this 13th day of September, 1917.

WALTER GLAESER.
